UNITED STATES PATENT OFFICE

2,034,926

SYRINGE

Lawrence M. Smith, Chicago, Ill.

Application August 16, 1933, Serial No. 685,307

3 Claims. (Cl. 128—239)

This invention relates to an improvement in syringes, and more particularly to syringes of the character commonly used as vaginal douches, although the invention may have other and various uses as will be apparent to one skilled in the art.

In the past, many and various types of syringes and vaginal douches have been developed, but these devices formerly known were not as efficient as is desirable. Some of these heretofore known devices depended to some extent upon a slight scouring action for cleansing and others depended upon a substantial dilation of the vaginal wall caused by liquid pressure alone. Both these methods taken individually are not sufficient to insure perfect cleansing. In addition, none of these previously known devices of which I am aware utilized the outflow of liquid as an aid to cleansing, but were dependent entirely upon the cleansing action of the liquid as it left the nozzle of the syringe or douche. Also, in every instance of which I am aware, devices heretofore have been made of a material which, if not handled with great care, could cause abrasions or other injuries to the vaginal wall.

With the foregoing in mind, it is an object of this invention to provide a vaginal syringe or douche made of a flexible, resilient material non-injurious to the vaginal wall.

It is also an object of this invention to provide a device of the character described constructed so as to utilize the douching liquid not only upon its discharge from the nozzle or end of the device, but also upon the exit of the liquid from the vagina for cleansing purposes.

Still another object of this invention is the provision of a vaginal douche or the like which insures the proper velocity of discharge of douching liquid at the nozzle end of the device through great variations of liquid pressures entering the device.

Still a further object of this invention is the provision of a device of the character described which insures a positive expansion of the vaginal wall causing the cleansing liquid to come in contact with the entire surface, the normal folds being smoothed out by the dilation of the wall.

It is still a further object of this invention to provide a vaginal douche or the like incorporating in the one element positive expansion or dilation of the vaginal walls, dilating liquid pressure within the vagina, and a scouring action to insure cleanliness.

While some of the more salient features, characteristics and advantages of the present invention

have been above pointed out, others will become apparent from the disclosures hereinafter.

The invention includes these and other features of construction and combinations of parts, hereinafter described, and shown in a preferred form in the drawing, as more particularly indicated by the claims.

On the drawing:

Figure 1 is a fragmentary elevational view of a device embodying principles of the present invention shown connected to a cleansing liquid supply conduit.

Figure 2 is an enlarged vertical sectional view of the device itself taken substantially as indicated by line II—II of Figure 1.

Figure 3 is a transverse sectional view of the device taken substantially as indicated by the line III—III of Figure 2.

Figure 4 is a transverse sectional view through the nozzle of the device taken substantially as indicated by the line IV—IV of Figure 2.

Figure 5 is a fragmentary sectional view similar to Figure 2 showing a slightly modified form of connecting member.

As shown on the drawing:

In the illustrated embodiment of the present invention the main or body portion of the device is a flexible resilient member 10, preferably made of a suitable rubber composition that will cause no physical injury even though the device may be carelessly handled. This member 10 is provided with an irrigation passage 11 therethrough. In linear dimension, the diameter of the member 10 is preferably not less than one-eighth of the length of the member, whereby the member insures a positive dilation of the vaginal walls when inserted. The forward end of the member is rounded as indicated at 12 to enable a gentle entrance.

At the rear end thereof, the member is provided with a shouldered connecting member 13 flanged as at 14 to afford a seat for a washer 15 which abuts the rear end of the member 10 around the passage 11. The inner end of the connecting member 13 is threaded as indicated at 16 so that the connector will stay anchored during use in the passage 11. The threads are preferably relied upon for their frictional gripping action and the member 10 is preferably not internally threaded along the passage 11. The connector is very easily removed due to the resiliency of the member 10 for cleansing purposes. As seen in Figure 1, the device is shown attached through the connector 13 to a suitable liquid conduit 17 which may be the tube leading from a fountain

syringe, a douche bag, or any other suitable conduit.

At the forward end thereof, the member 10 is provided with a nozzle 18 flanged as at 19 and 5 provided with an inner threaded end 20 for insertion in the irrigation passage 11. The nozzle is easily removable and is held in position in the same manner as is the connector 13. Contrary to the construction of the connector, the central 10 passage through the nozzle does not extend entirely therethrough but terminates just beyond a plurality of lateral apertures 21, seen more clearly in Figure 4. As indicated clearly in Figures 2 and 4, the discharge apertures 21 are located 15 in different lateral planes, and those located in one plane are disposed at a different angle from those located in another plane.

Located at any desirable or suitable point within the irrigation passage 11 is a centrally 20 passaged Venturi-like or metering member 22 provided with an external flange 23 which is resiliently gripped by the inner walls of the member 10 to hold the metering device in position. The aperture through the metering device is obviously smaller than the irrigation passage 11 and 25 consequently affords a partial restriction to fluid flow through the passage 11, thereby causing a change in velocity of the cleansing fluid. In this manner, the velocity of cleansing fluid when discharged through the orifices 21 may be increased.

The connector 13, the nozzle 18, and the metering member 22, may each be formed of any suitable material, but are preferably of hard rubber or a phenolic or alcoholic condensation product. 30 Outlet passages in the form of substantially semicircular grooves are formed integrally in the external surface of the member 10. Any desired number of these grooves may be provided. As illustrated, two grooves diametrically opposed to 35 each other are provided. The grooves may be of any desirable size, but preferably have a total flow capacity approximately equal to one-half that of all of the orifices 21. By this means, substantially half of the douching fluid is prevented 40 from immediately leaving the vagina, thus causing to some extent a further dilation of the vaginal walls due to the fluid pressure and also assuring proper cleansing.

It will be apparent that thorough cleansing will 45 result even to the very bottom of all folds or crevices in the vaginal wall. One of the most important parts of the vaginal tract to be cleansed is the deep fold between the cervix of the uterus and the vaginal wall. Great difficulty has been experienced heretofore in cleansing 50 this region, but a complete insertion of the present invention causes a dilation of the vagina and brings the rounded or button-like head of the nozzle 18 in position to cover the os uteri and elevate the cervix, thereby opening the afore- 55 said deep fold for thorough cleansing, and prevent the douching fluid from entering the uterus.

In the structure illustrated in Figure 5, a slightly different form of connector 25 is shown 60 which is provided with a smooth inner end 26 for insertion in the irrigation passage 11. This connector is also flanged as at 27 to properly seat a washer 28 against the rear end of the member 10 around the irrigation passage. The connector is 65 also shouldered as is the connector 13 to insure a proper connection to the fluid conduit.

With the inner end of the connector smooth 70 as at 26, other means must be employed to hold the connector in position during use, and to this 75 end an apertured cap 29 of any suitable material

is provided. This cap is provided with an inner boss 30 bearing against the flange 27 of the connector and is also provided with an outer internally threaded flange 31 engaging the exterior surface of the member 10 to hold the parts in 5 position. With this construction, it will at once be apparent that the member 10 may be swivelled or rotated around the connector 25 relatively thereto, and the conduit attached to the connector will not be twisted.

The rotation of the member 10, aided materially by the edges of the grooves 24 affords a scouring action to thereby further increase the 10 cleansing possibilities of the device.

In use, any suitable form of clamp or stop 15 cock may be used in the conduit 17. The device is inserted in the vagina, the clamp or stop cock released and the douching fluid permitted to be 20 discharged through the orifices 21, and the velocity of discharge of the fluid being effected as 25 above explained by the metering member 22. The outflow of the fluid from the vagina will be only approximately one-half as rapid as the inflow, as aforesaid, due to the capacity of the 30 grooves 24. The outflow of fluid in the grooves 24 will also exercise a cleansing action and insure 35 removal of any accumulated secretions. During the douching process, the member 10 is preferably rotated as explained above, thereby adding to the cleansing with a resultant scouring 40 action. During the cleansing process, the vagina will be dilated a material extent by the member 10 and also dilated a further extent by the liquid pressure therein, which, taken in conjunction with the scouring action and the cleansing 45 action of the fluid during its outflow in the passages 24, insures a positive and thorough cleansing.

I am aware that many changes may be made 40 and numerous details of construction may be varied through a wide range without departing 45 from the principles of this invention, and I, therefore, do not purpose limiting the patent granted hereon otherwise than necessitated by the prior art.

I claim as my invention:

1. In a douche of the character described, a 50 resilient member having an irrigation passage therethrough, nozzle means on the end of said member, and a plug-like member in said irrigation passage having a passage therethrough of less size than said irrigation passage to permit a variance in velocity of the douching fluid, said member being selectively locatable at any desirable point relative to said nozzle.

2. In a douche of the character described, a 55 resilient member having an irrigation passage therethrough and being of sufficient size to insure expansion of the vaginal walls, said member being of sufficient length to project well without the vagina even when inserted to the full depth of the vagina, said member also having a plurality of longitudinally extending drain 60 grooves in the outer surface thereof of a capacity not exceeding one-half the amount of fluid 65 passable through the douche, and a swivel connection associated with the outer end of said member to establish communication between said irrigation passage and a supply conduit to permit rotation of said member relatively to said supply 70 conduit while inserted in a vagina.

3. In a douche of the character described, a 75 resilient member having an irrigation passage therethrough and being of a sufficient size to insure expansion of the vaginal walls, said mem-

- ber having a plurality of longitudinally extending grooves in the outer face thereof to function as drain passages, means associated with the inner end of said member having discharge openings therein of a capacity substantially twice that of said grooves, a selectively disposable plug-like member in said irrigation passage and having a
- passage therethrough of less size than said irrigation passage, and a swivel connection associated with the outer end of said member for establishing communication between said irrigation passage and a fluid supply conduit. 5

LAWRENCE M. SMITH.
